Patented Aug. 17, 1915.

UNITED STATES PATENT OFFICE.

ROLLIE C. SAGE, OF ARROWROCK, IDAHO.

ELECTRIC WATER-HEATER.

1,150,390.

Patented Aug. 17, 1915.

Specification of Letters Patent.

Application filed April 14, 1914. Serial No. 831,810.

To all whom it may concern:

Be it known that I, ROLLIE C. SAGE, citizen of the United States, residing at Arrowrock, in the county of Boise and State of Idaho, have invented certain new and useful Improvements in Electric Water-Heaters, of which the following is a specification.

My invention relates to new and useful improvements in electric heaters, the primary object of my invention being the provision of an electrically heated boiler which may be used in place of the ordinary boilers now employed in heating dwellings and the like by hot water or steam.

A still further object of my invention is the provision of an electrically heated boiler including a plurality of separate heating coils having a common return conductor and independent feed conductors, whereby the current may be selectively shut off from any one or more of the coils.

A still further object of my invention is to provide simple means for mounting the heating coils within the boiler casing or shell in such a manner that they may be readily removed for repair. And a still further object of my invention is to provide a novel form of heating coil construction.

With these and other objects in view, my invention will be more fully described, illustrated in the accompanying drawings, and then specifically pointed out in the claims which are attached to and form a part of this application.

In the drawings:—Figure 1 is a central, vertical sectional view taken through my improved boiler; Fig. 2 is a transverse sectional view taken on the line 2—2 and looking in the direction of the arrows; Fig. 3 is a central longitudinal sectional view of one of my improved heating coils removed from the boiler.

Corresponding and like parts are referred to in the following description and indicated in all the views of the drawings by the same reference characters.

I have illustrated my improved boiler as connected between a water supply pipe 10 which is the return pipe from the radiators and a pipe 11 leading to the radiators. The pipe 10 is provided, preferably at a point immediately below the boiler which, as a whole, is indicated by the numeral 12, with a branch or overflow pipe 13 which leads to an overflow tank, not shown, preferably

located at a level above that of the highest radiator in order to insure proper pressure and allow of the expansion of water during its heating.

The boiler 12 includes a tubular shell or casing 14, preferably circular in cross section and having its ends externally threaded to receive the internally threaded boiler flanges 15. The adjacent ends of the pipes 10 and 11 are threaded to receive flanged couplings 16 and the boiler is secured or connected between these pipes by means of boiler heads 17 in the form of plates provided with central openings at least equal in size to the interior bore of the pipes. Packing rings 18 and 19 of rubber, or other suitable material, are interposed between the couplings 16 and boiler heads 17 and between the boiler flanges 15 and boiler heads 17 and bolts 20 having nuts 21 and bolts 22 having nuts 23 secure the boiler heads to the boiler flanges and to the flanges of the couplings, respectively.

Each boiler is provided with a plurality of suitably spaced, preferably symmetrically disposed, heating elements, each indicated as a whole by the numeral 24. Referring specifically to Fig. 3, it will be seen that each of these heating elements is formed by winding a resistance wire 25 in the channels of an external thread 26 formed throughout the greater portion of the length of a tubular supporting member 27 of fiber or other non-current conducting material. The ends of the supporting member 26 are provided with metallic ferrules 28, preferably formed of brass or copper and the ends of the coils 25 are electrically connected to these ferrules by binding screws 29, the screws not only serving to connect the wire to the ferrules, but also to secure the ferrules against disengagement from the ends of the supporting member or tube 27. The threads cut in the tubular supporting member 27 serve to properly space adjacent convolutions of the heating coils from each other to prevent short-circuiting, holding all parts of the coil in fixed position under all circumstances. These heating coils extend longitudinally within the casing, being peripherally arranged therewith and detachably supported each by a pair of vertically aligned spring clips 28'. As best shown in Fig. 2, each of these clips is formed from a single strip of resilient metal bent substantially U-shaped with the intermediate

portions of its side arms bowed outwardly to conform to the contour of the ferrules or caps 29 of the coil which they are to surround. In each instance, one of the supporting clips of the coil is secured to the boiler shell by a screw 30 extending through the intermediate portion of the clip and through a packing member 31 of insulating material and carrying at its outer ends cooperating binding nuts 32 adapted to receive the terminal 33 of an electric feed wire 34. By this means, it will be seen that the clips so mounted are insulated from the body of the boiler. On the other hand, the other supporting clip of each coil is directly and electrically connected to the shell of the boiler by a screw 35. Some portion of the boiler, preferably the lower boiler flange 15, is provided with a binding screw 36 to receive the terminal 37 of a common return wire or conductor 38.

Any suitable arrangement of switches, not shown, as it forms no part of my invention, may be provided for selectively shutting off the flow of current to any one or more of the heating coils in order to permit regulation of heat.

In operation, a constant circulation or upward flow of water through the boiler is maintained, as is customary, and current passed to the heating coils from the feed wires 34 through the binding post 30 and connected clips 28 to the ferrules of the heating coils which they support. From these ferrules, the current passes through the wire coils to the ferrules at the opposite end of the coils and through the clips encircling these latter ferrules to the shell of the boiler and thence to the common return wire 38.

The clips provide a simple and effective supporting means for the heating elements and insure good electrical connections. Furthermore, any heating element may be readily removed from its supporting clips upon removal of the adjacent boiler head and replaced by a new one in case the wire, due to any improper operation of the boiler, should become burnt out. If the heating coils are properly formed, however, they should be practically indestructible unless the level of water in the boiler is permitted to fall below them.

Although I have illustrated and described my improved boiler in all its details, it will of course be understood that I do not wish in any way to limit myself to the specific details of construction there shown, as various minor changes, within the scope of the appended claims, may be made at any time,

without in the slightest degree departing from the spirit of my invention.

Having thus described the invention, what is claimed as new is:

1. An electric heater comprising a support of electric conducting material, pairs of holders of electric conducting material attached to the support, one holder of each pair being electrically connected with the support and the remaining holders being electrically insulated from the support, a lead wire connected with the support, a lead wire for each of the electrically insulated holders connected thereto, and a plurality of electric heating units having contact terminals to make electric connection with the pairs of holders, said units being detachably connected with the support. 65 70 75

2. An electrically heated boiler, the same comprising a metallic casing for receiving the water to be heated, a plurality of electric heating elements removably fitted within the casing, each consisting of a resisting coil and terminal contacts, a pair of holders for each heating element formed of electric conducting material and arranged within the casing and supported thereby, one holder of each pair being insulated from the casing and the other holder being in electric connection with the casing, a lead wire 80 connected with the casing and a lead wire for each of the holders that is electrically insulated from the casing. 85 90

3. An electrically heated boiler including a boiler casing, a plurality of supporting clips mounted interiorly of the casing and arranged in pairs, one clip of each pair being insulated from the casing and the other in electrical connection therewith, means for supplying current to those clips insulated 95 from the casing, and a plurality of heating elements adapted to be supported one by each pair of clips, each of said heating elements including a tubular supporting member of fiber closed at its ends with metallic 100 ferrules adapted for engagement in the clips, the intermediate portion of said body being exteriorly threaded, a resistance wire wound in the threads and extending between the ferrules, and binding screws 105 passed through the ferrules and into the fiber supporting member to secure the terminals of the wire to the ferrules and the ferrules to the supporting member. 110

In testimony whereof I affix my signature 115 in presence of two witnesses.

ROLLIE C. SAGE. [L. S.]
